(54) **FLAX & HEMP MACHINE**

(76) Inventor: **William Van Duzer**

The invention consists in this Sisler's Patented machine, in this combination and arrangement of parts, to the end of the same, William Van Duzen, will prosecute his machine, to breaking hemp and flax.

This machine consists of two long vertical upright posts, four eight to ten feet in length each, must stand straight & firmly, and be secured with other timber braces so as to form a two storied frame, resembling that of a saw mill in which the saw gate stands, which frame is to be in the clear from eight to ten feet high, and from four to twelve, or any other size that may be found more convenient, over one third of the distance from the bottom to the top of the uprights, or posts, there is more than one break or breakers, placed in horizontality across the frame and wider at one end than the other, in thickness to the frame. Posts of the common hemp break, and the frame must be fastened within the uprights, extended to certain more than four posts to be placed across the bottom of the frame, except that the four or five last posts are to stand a discretionary distance above horizontally, so that when the hemp is placed just below at the front post of the break the mouth of the stalks is very small but slopes in proportion to the rear so that at the front the stalks are very crooked but by turning the hemp or flax counterturn to the rear the breaking is completely finished.

This frame, resembling both in form and motion a common saw gate except in the front and rear sliders which are to slip in grooves in the main frame and must be done in number of the stalks for one passed on each end of the several stalks; third in the machine is to receive motion from a crank and flywheel and power from two horses water or steam, and to be guided in all according to circumstances the inventor William claims the right of using a fly wheel and any other apparatus and especially the flywheel may be attached to the bottom or top of the machine as the operator may be. He invents claims the right of using as machine for breaking the hemp, William Van Duzen, to the right of the signature of William Van Duzen, witness,
